UNITED STATES PATENT OFFICE.

HARRY H. ENGLEMAN, OF DEFIANCE, OHIO.

APPARATUS FOR MANUFACTURING OIL-GAS.

SPECIFICATION forming part of Letters Patent No. 423,516, dated March 18, 1890.

Application filed January 14, 1889. Serial No. 296,283. (No model.)

To all whom it may concern:

Be it known that I, HARRY H. ENGLEMAN, a citizen of the United States, residing at Defiance, in the county of Defiance and State 5 of Ohio, have invented certain new and useful Improvements in an Apparatus for Manufacturing Oil-Gas; and I do hereby declare that the following is a full, clear, and exact description of the invention, which will enable 10 others skilled in the art to which it appertains to make and use the same, reference being had to the accompanying drawings, and to the letters of reference marked thereon, which form part of this specification.

15 My invention relates to an apparatus for manufacturing a fixed gas from petroleum-oils, and has for its object the decomposition of the petroleum-oil without residuum, and a proper dilution of the gas evolved with atmospheric 20 air, whereby the crude petroleum as received from the earth may be successfully vaporized by a system of destructive distillation and purification that shall result in a maximum product of gas adaptable for use for either 25 illuminating or fuel purposes.

30 A further object is to treat the crude petroleum in the successive stages of purification, decomposition, vaporization, and admixture with atmospheric air to support combustion within an organized apparatus that shall be inexpensive in construction, convenient of management, and that shall require a minimum expense in delivering the gas to the gas- 35 holder in condition to be utilized for illuminating or heating purposes.

35 A further object is to incorporate with the petroleum-oil prior to the final stage of decomposition a proper proportion of caustic solution, preferably lime-water, to desulphurize 40 the same, and by which means any carbonic-acid gas that may be present is deprived of a portion of its oxygen and converted into carbonic-oxide gas within a chamber in which the oil and solution are raised to a temperature 45 of 212° Fahrenheit prior to being injected into retorts for the conversion of the same, as well as the paraffine and all tarry matter into a permanent gas.

50 A further object is to pass the gases and tarry substance and paraffine over some form of the chlorides, preferably chloride of sodium, by which the tarry and paraffine pro-

ducts are decomposed, and whereby the gases passing into the chamber or retort may be more perfectly disintegrated and vaporized. 55

A further object is to pass the same gases and residuum over some of the metallic oxides, preferably binoxide of manganese, by which the chlorine gas may be taken out of the gases and oxygen be thrown off to mingle 60 with the gases and aid in the production of carbonic oxide.

A further object is to incorporate within the disintegrated oil as it leaves the primary chamber and enters the heated retort a volume of superheated atmospheric air, by which the oxygen may combine with any carbonic acid that may remain within the distillates to convert the same into a carbonic oxide to effectually insure against the presence of carbonic-acid-gas in the product of distillation. 70

A further object is to construct the retort with spiral deflectors that shall revolve the hydrocarbons in passing from the point of entry to the exit, whereby to cause the entire 75 body of the same to be subjected to the same degree of heat.

A further object is to subject the vaporized product of destructive distillation to a final washing and incorporation with atmospheric 80 air prior to being stored for use.

The invention consists in the parts and combination of parts hereinafter described, and pointed out in the claims.

In the drawings, Figure 1 is a longitudinal 85 vertical view through the mixing-chamber, the retort, and washing-chamber, with a portion of a steam-boiler shown in elevation. Fig. 2 is a plan view of the mixing-chamber and retort, with the top removed to disclose the interior, 90 the washing-chamber being also in plan. Fig. 3 is a longitudinal sectional view of the retort on lines *x x*, Fig. 1. Fig. 4 is a detail view of an injector and the pipes in communication therewith. Fig. 5 is a sectional view of one 95 section of the retort, the front half thereof being removed to disclose the interior arrangement of the same.

In describing the construction of my gas-generating apparatus I will commence with 100 the feed of the oil and follow the process of purification, distillation, and admixture of air in their order.

A designates an oil-receptacle, and B a re-

ceptacle for caustic solution, preferably lime-water, these receptacles being preferably located above the main portion of the apparatus to allow a gravity-feed through pipes C and C', respectively.

D designates a steam-tight chamber, which will be hereinafter referred to as a "mixing-chamber," and into which pipes C and C' are led and united to a perforated pipe C'.

10 E designates a steam-boiler located contiguous to the mixing-chamber, and from which extends a pipe E', leading into mixing-chamber D and formed into a convoluted coil E'', as shown in plan view in Fig. 2, the pipe at the 15 lower and inner end thereof being bent at a right angle and returned to the pump, by which means the condensation is returned, or the water of condensation may be allowed to run to waste. This being immaterial, it is

20 deemed unnecessary to illustrate the connections with the waste-pipe.

F designates the furnace, which may be of any preferred construction, for the utilization of heat resulting from either the combustion 25 of the gas resulting from the process herein described or from any preferred fuel.

G designates the retort composed of a series 30 of pipes H, lying in parallel relation and connected by couplings H' to establish a connection throughout the length thereof, I being pipes connected at the rear end of the furnace to lie in parallel relation above the retort-pipe and separated therefrom by a plate J, interposed between the furnace and 35 said pipes. Each coupling H' is provided with screw-plugs H'', inserted in the end thereof, by which means the plug in the first pipe H of the retort may be removed and a quantity of chloride of sodium placed there-

40 in, whereby the matter to be vaporized is caused to pass over the same, thereby causing the chlorine gas to incorporate with the vapors and assist in disintegrating the tarry substance. The plug H'' of the second pipe

45 of the retort is also unscrewed and some of the metallic oxides (preferably binoxide of manganese) placed therein, whereby when the vapors pass through the same the oxygen of the binoxide yields up a certain portion of 50 oxygen to mingle with the carbon that may remain, converting the same into carbon dioxide. The outer end of pipe I is bell-shaped to receive an induced current of atmospheric air, and is extended in the direction of the 55 length of the furnace and returned in parallel relation, being coupled to a fan-blower K, from which a pipe K' extends to a nozzle L, inserted into the first pipe H of the retort, as will be presently explained.

60 M designates a pipe extending from the interior of mixing-chamber D to the nozzle L, inserted into the pipe H of retort G, by which means the desulphurized petroleum-oil is conveyed to the retort.

65 N designates a pipe leading from the upper portion of mixing-chamber D to nozzle L, by

which any of the more volatile vapors of the petroleum-oils sprayed into the mixing-chamber may escape and be led to the nozzle L, to be injected into the retort G.

O designates a pipe leading from the last of the series of pipes constituting the retort G to a chamber P, filled with an alkaline solution, the portions of pipe O within chamber P being perforated to allow the gas to 75 escape to be thoroughly cleansed by passing through the solution in chamber P.

Q designates a vertical pipe leading from chamber P and extending to an injector R, from which a pipe R' leads to the gas-receiver. 80 (Not shown.)

S designates a fan-blower connected with injector R by a pipe S', the blowers K and S being driven by power generated in the boiler E.

85 The pipes H of the retort and the vertical pipe Q are each provided with stationary spirals T, by which to cause the fluid to traverse a tortuous course in passing through the retort and vertical pipe, respectively, the object 90 being in the first instance to cause the fluid to be subjected to the equal temperature surrounding the outer periphery of the pipes, as well as to revolve and intermingle the solution, petroleum-oil, and air, while being disintegrated, and in the vertical pipe Q to cause 95 the condensation to return to the chamber P.

U designates a pipe connected with chamber P, designed to drain from the surface of the alkaline solution any impurities that may 100 collect, the said pipe, as well as pipe M, being formed with a curved portion to act as a seal.

In operation oil is permitted to flow from receptacle A through pipe C to pipe C''. The solution is permitted to flow from receptacle 105 B through pipe C' to pipe C'', the two fluids meeting and being sprayed upon coil E'' in chamber D, which has been previously heated to a temperature of 212° Fahrenheit by steam from boiler E, whereby a thorough intermix-

110 ture of the hydrocarbon fluid and the caustic solution is effected, and as a result the oil is desulphurized and the oil partially disintegrated, when the intermingled fluids are passed through pipe M into the nozzle L and 115 injected into the first pipe of the retort. The more volatile vapors arise to pass through pipe N to the nozzle, and a volume of super-

120 heated atmospheric air is forced through pipe K' into said nozzle, wherein the heated air, the volatile vapor, and the liquid petroleum are intimately intermingled and injected into the retort, which has been previously heated to from 600° to 900° Fahrenheit. The entire

125 mass as thus intermingled is caused to pass through the several pipes H of retort G. Passing through the first pipe H, it is caused to pass over the chloride and receive the benefit of the chemical action thereof, and passing through the second pipe H the binoxide of

130 manganese effects the chemical action of withdrawing one-third of the oxygen from the car-

bon, thereby converting any carbon that may remain into carbonic-oxide gas, the fluid being caused to revolve and be brought in close contact with the inner surface of the pipes of the retort by reason of the spirals T, and is in this manner fully vaporized, the gas being caused to pass through pipe O into washing-chamber P, where any ammonia that may be in the gas is eliminated. From the washer P the thoroughly-purified gas rises through pipe Q to the injector R, and in its tortuous course any condensation may return by way of the spiral to the chamber. The gas in injector R is met by a current of atmospheric air supplied through pipe S' by means of blower S, and as thus intermingled is passed to the receiver to be used as an illuminant or for fuel, the product being particularly adaptable for use in the manufacture of steel and glass by reason of the even flow and the intense heat of the flame.

What I claim is—

1. In an apparatus for the manufacture of gas from petroleum-oil, the combination, with the mixing-chamber, of a perforated pipe extending through the top of the same, an oil-reservoir and a desulphurizing-solution reservoir, pipes connecting said reservoirs with the perforated pipe, a steam-pipe located in the bottom of the chamber, adapted to heat the said chamber, a retort arranged adjacent to said heating-chamber, and a fluid and vapor pipe connecting said retort and heating-chamber, whereby both oil and vapor are car-

ried into the retort, substantially as shown 35 and described.

2. In an apparatus for the manufacture of gas from petroleum-oils, the combination, with a mixing-chamber, of a perforated pipe extending through the top of the same, a steam- 40 pipe located in the bottom of the chamber, the oil and caustic-solution reservoir, and pipes connecting said reservoir with the perforated pipe, a retort arranged adjacent to the mixing-chamber, fluid and vapor pipes 45 connecting said retort and mixing-chamber, and an air-supply pipe communicating with the retort at the same point as the fluid and vapor pipes and a blower for forcing the air into the same, as and for the purpose de- 50 scribed.

3. A chamber for washing the gas evolved from a retort and provided with a suitable seal and overflow pipe, a pipe connecting said washing-chamber and retort, an upwardly- 55 extended pipe having a spiral deflector arranged therein, said pipe being connected to one end of the washing-chamber, and an air-blower connected to the upper end of the said pipe, substantially as shown and described. 60

In testimony that I claim the foregoing as my own I hereby affix my signature in presence of two witnesses.

HARRY H. ENGLEMAN.
